UNITED STATES PATENT OFFICE.

FREDERICK DANIEL GROSS, RANDALL PORTER AKINS, AND JOHN WILLIAM BUCHER,
OF DENVER, COLORADO.

FLOTATION APPARATUS AND PROCESS.

1,401,535.

Specification of Letters Patent. Patented Dec. 27, 1921.

Application filed November 5, 1919. Serial No. 335,951.

To all whom it may concern:

Be it known that we, FREDERICK D. GROSS, RANDALL P. AKINS, and JOHN W. BUCHER, citizens of the United States, residents of 5 Denver, Colorado, have invented certain new and useful Improvements in Flotation Apparatus and Processes, of which the following is a specification.

Our present invention relates to improvements in apparatus for the flotation of sulfids or other mineral substances, so as to 10 separate them from the other constituents of the ores in which they occur.

In the flotation process, the frothing of 15 the mineral contents depends upon bringing of the mineral particles into intimate contact with air bubbles, so that these mineral particles attach themselves to the minute air bubbles and are thus carried to the surface 20 of the liquid and floated, while the other constituents of the ore do not attach themselves to the bubbles and are thus not carried to the surface.

The bubbles of air rising to the surface 25 of the liquid and carrying the mineral particles with them, form what is called in metallurgical parlance, froth, and this froth is allowed or caused to overflow a weir at the top of the tank and is collected for further treatment. The other constituents of 30 the ore are withdrawn from the tank below the frothing surface. Two embodiments of our invention are shown in the accompanying drawings in which:

Figure 1 is a transverse sectional view and Fig. 2 a longitudinal sectional view of an apparatus comprising three frothing compartments with spitzkasten on the side for the overflow of the froth and the settling back 40 of the other constituents of the ore.

Figs. 3, 4 and 5 are respectively transverse sectional views and a longitudinal sectional view of a modified form of apparatus comprising two frothing compartments, and two 45 spitzkasten or settling compartments.

In these drawings the same or similar reference characters indicate identical or similar parts and are so referred to in the following description. The machine consists essentially 50 of a tank "A" partially or completely inclosed and divided by partitions A' into a plurality of compartments which are in communication at the bottom by ports U. Located in each compartment to one side of 55 the center thereof is a vertically disposed

rotor, mounted on the horizontal shaft N journaled in suitably packed bearings Q and which may be driven by suitable means, as for instance the pulley O. Each rotor is made up of spiral vanes B leading from the outer periphery toward the center, and sides B' inclosing such vanes, thereby providing spiral passages E between the vanes B and the sides B' which lead from the outer periphery toward the center. Around the central shaft is a cylindrical screen F, the vanes B and the passages E terminating at this screen. On the top of the tank A above each rotor is an air chamber C connected to the atmosphere by means of a pipe D in which is located a regulating valve D'. The screen F is extended into the space at the side of its rotor and surrounding that portion of the screen is another cylindrical screen G to further assist in breaking up the air into 75 minute bubbles and causing froth.

The spitzkasten in Fig. 1 is shown at H and is provided with a solid baffle I for the purpose of directing the flow of the pulp and the return of the solids, and a perforated baffle J for the purpose of directing the flow and also of breaking up any wave motion so as to present a rather quiescent surface to the liquid.

The overflow weir for the froth is shown 85 at K which determines the froth level T. The water level is shown at L and is regulated by the height of the discharge pipe S, which being on a swivel gives means for adjusting.

For regulating the velocity of flow or the height of discharge of the frothed material from the frothing compartment to the spitzkasten we provide a slidable gate M.

Pulp is fed into the machine at R and delivered to the underside of the rotor and advanced from one compartment to the other through the openings U.

The overflowed froth is carried away 100 from the machine by means of the launder V. In the machine shown in Figs. 3, 4 and 5, we provide a tank divided into two compartments, and locate in each compartment two sets of baffles I' and J', the annular screen G being omitted in this form. We 105 also provide in this form launders for the overflowed or decanted froth on opposite sides of the machine as indicated at V' V'.

Inclined planes P serve the purpose of advancing the non-mineral or non-floatable 110

content toward the discharge end of the machine while in the center of these inclined planes *P* are return circulating ducts or passageways *W* leading back toward the front end of the machine, which passageways or ducts narrow as they go back toward the front end of the machine, so as to increase the velocity of the pulp and keep the passages clear. These return passages are for the purpose of keeping the rotor in balance and maintaining a constant water level in all compartments of the machine. In this form the heavier parts of the non-floatable material are discharged from the tank *A* through the pipe and valve shown at *S'*, and the lighter portions of the non-floatable material may be carried up with the water through the passage *X* and overflow the adjustable weir *Y* into the launder *Z* and thence to the pipe *S*.

Having thus described the construction and arrangement of parts of the machine, the operation may be described as follows:

Finely pulverized ore and water with a small amount of frothing agent are fed into the machine at "R," filling the machine or tank to the water level "L." As the rotor revolves in the direction of the arrow shown in the air chamber "C," air is trapped in the channels "E" between the vanes "B" and the sides of the vanes "B'" and as the vanes reach the water level "L" this air is forced with the water and ore toward and through the central screen "F." In passing through this center screen the air is broken into small bubbles which pass outward as shown by direction of arrows in Figs. 2 and 5, and outward through screen "G" shown in Fig. 2.

The desired amount of air for proper froth formation is admitted to the air chamber "C" by means of the controlling valve *D'*.

As the frothed material passes into the spitzkasten under the slidable gate "M" in Fig. 1, or through the screen "F" in Fig. 4, it strikes the solid baffles "I" or "I' I'" and passing upward flows toward the weir "K." The heavier unfrothed mineral and the non-frothable material circulate downward, and are carried back and into the rotor and again subjected to an aeration. In the apparatus shown in Figs 3 to 5 the non-frothable material circulates through the screen "F" onto the inclined plane "P" and is soon advanced through the machine and out toward the discharge, while the lighter material is carried back through the passage "W" and given a second treatment through the rotor.

Having thus described our invention what we claim is:

1. The herein described method of separating minerals by the flotation process which consists in successively isolating and

commingling definite quantities of a froth producing mineral containing liquid and air to thoroughly commingle and aerate the same, and thereafter directly releasing said definite quantities of aerated liquid below the surface of a body of similar liquid to effect frothing thereof.

2. In a flotation apparatus, a suitable tank having an open and closed compartment, means for admitting a regulable quantity of air to said closed compartment, a vertically disposed rotor journaled in said closed compartment on a horizontal axis and having blades formed to segregate and draw toward the axis both air and liquid, said rotor having a direct discharge into the body of liquid in said open compartment below the surface of the liquid therein to produce froth, and an overflow weir for said open compartment for the froth.

3. In a flotation machine, a tank having a closed compartment and an open compartment, a rotor in said closed compartment rotating on a horizontal axis and adapted to be partially submerged, said rotor having spiral passages leading from its periphery toward the center, a perforate member near the center through which the mixture of air and liquid is forced into said open compartment, and an overflow weir for said open compartment to remove froth, said overflow weir being above the level of said perforated member.

4. In a flotation apparatus, a tank having an open and a closed compartment with means for supplying air in regulable quantities to said closed compartment, a rotor journaled in said closed compartment adapted to be partially submerged and having a passage leading from the periphery to near the center of the rotor, an annular screen within said rotor at which said passage terminates, said screen being extended into said open compartment, means for maintaining the liquid level in said tank above the top of said screen, and an overflow weir for said open compartment.

5. In a flotation apparatus, a tank having a pair of adjoining compartments communicating at the bottom, a rotor mounted in one compartment and having a passage leading from the periphery toward the center, a cylindrical screen at the center of the rotor at which said passage terminates, said screen having a portion projecting into the other compartment, means for maintaining a liquid level in said tank above the top of said screen, baffles located in said other compartment above said projecting screen portion, and an overflow weir for said other compartment.

6. In a flotation apparatus, a tank having a pair of adjoining compartments communicating at the bottom, a rotor mounted in one compartment and having a plurality

of spiral passages leading from the periphery toward the center, a cylindrical screen at the center of the rotor at which said passages terminate, said screen having a portion projecting into the other compartment, means for maintaining a liquid level in said tank above the top of said screen, baffles located in said other compartment above said projecting screen portion, a deflector located over said communication between the compartments, and an overflow weir for said other compartment.

7. In a flotation apparatus, a containing tank having a closed compartment and an open compartment, a vertically disposed rotor in said closed compartment having passages leading from the periphery toward the center, a cylindrical screen at the center

of said rotor at which said passages terminate, said screen having a portion extending into the open chamber, baffles in said open compartment above the level of said screen portion, a conduit leading from said open compartment to said closed compartment, an overflow weir on said open compartment to remove froth, means for maintaining a liquid level in said compartments above the top of the screen, and means for removing any desired proportion of the non-frothing material from said open compartment.

In testimony whereof, we affix our signatures.

FREDERICK DANIEL GROSS.
RANDALL PORTER AKINS.
JOHN WILLIAM BUCHER.
